CLAIM

The ornamental design for an espresso machine, as shown and described.

DESCRIPTION

FIG. 1 is a perspective front view of an espresso machine in accordance with the present invention;

FIG. 2 is an elevational front view of the espresso machine in FIG. 1;

FIG. 3 is an elevational rear view of the espresso machine in FIG. 1;

FIG. 4 is an elevational left-side view of the espresso machine in FIG. 1;

FIG. 5 is an elevational right-side view of the espresso machine in FIG. 1;

FIG. 6 is a top plan view of the espresso machine in FIG. 1;

FIG. 7 is a bottom plan view of the espresso machine in FIG. 1; and,

FIG. 8 is a perspective rear view of the espresso machine in FIG. 1.

The broken lines shown in the drawings depict portions of the espresso machine which form no part of the claimed design.
